UNITED STATES PATENT OFFICE.

NATHANIEL GEAR, OF INDIANAPOLIS, INDIANA.

IMPROVED BOOT-LEG STIFFENER.

Specification forming part of Letters Patent No. 42,544, dated April 26, 1864.

To all whom it may concern:

Be it known that I, NATHANIEL GEAR, of Indianapolis, in the county of Marion and State of Indiana, have invented certain new and useful improvements in the manner of stiffening boot-legs and preventing them from wrinkling and chafing the ankles of the wearer, while they are quite free to conform to the bending of the leg in walking; and I do hereby declare the following to be a full, clear, and exact description of the same, reference being had to the accompanying drawings, making a part of this specification, in which—

Figure 1 represents a boot with my improvement attached. Fig. 2 represents a side view of one of the jointed stiffeners for preventing the leg from wrinkling, and Fig. 3 represents an edge view of the same.

I am aware that stiffeners for garments have been made, and that the backs of boots have been supported by metal bars or pieces, and that cloth tops for boots have been staid somewhat like cloth gaiters; but none of these stiffeners have been hinged or pivoted opposite to the joints in the leg of the wearer, so that while they keep the boot from wrinkling they shall not interfere with the free bending of the ankle or knee joints in walking or sitting.

My invention consists in the use of jointed stiffeners in boot-legs, so that while the boot-leg shall be prevented from wrinkling and chafing the wearer it may be free to bend at the ankle or knee joint, and thus be perfectly comfortable and easy to the user.

To enable others skilled in the art to make and use my invention, I will proceed to describe the same with reference to the drawings.

The boot A may be made in any of the usual forms, whether ordinary in length or top boots. A seam, B, is made down the sides of the boot, into which a jointed and steel-spring bar, C, is slipped, and which may be united to the boot solely by the rivet a, or by a screw, button, bolt, or any other fastening that will admit of the stiffener being removed or replaced.

The stiffener C has a joint, b, at or near that portion of it that comes opposite the ankle of

the user, and one or more joints, c, at or near that portion of it that is opposite the knee-joint of the user. These joints b c are so made as that they, as well as the boot-leg, will freely bend or yield with the joints of the leg, but be quite rigid in a line transverse to the joints. The lower end, d, of the stiffener is slightly curved, so as to fit the natural curve of the foot and boot where the upper joins the sole near the front of the heel, and this lower end, d, need not be riveted or fastened of necessity to anything, as it will rest against the upper and inner portion of the sole of the boot. It may, however, be fastened to the boot or to a strip of metal or other substance that extends across to the opposite side of the boot, and to which the stiffener on the opposite side of the boot-leg may be fastened. The stiffener in fine boots may be between the lining and outside and entirely concealed; but in coarse boots, which have no linings, it may be connected to the inside by rivets or otherwise without injury to the wearer. Many ways of uniting the stiffener to the boot-legs may be devised—as, for instance, the placing of the stiffener in the rear of the boot-leg—but having shown one feasible plan, I need not describe others. I prefer to make the bars of spring steel, but other metal may be used, and if designed for short boot-legs but one joint, b, is necessary; but for top-boots, extending above the knee, two or more joints are necessary. Besides stiffening the legs of the boots, these metal strips afford great support to the ankles of the wearer.

Having thus fully described my invention, what I claim therein as new, and desire to secure by Letters Patent, is—

The application of jointed metallic bars or stiffeners to the legs of boots, so as to keep them up and prevent them from wrinkling, while they are free to conform to the joints of the wearer, making them very comfortable and easy and avoiding chafing of the feet, substantially as described.

NATHANIEL GEAR.
